UNITED STATES PATENT OFFICE.

COLEMAN A. TERRY, OF NEW YORK, N. Y.

CORE-DRILLING APPARATUS.

No. 878,908.

Specification of Letters Patent.

Patented Feb. 11, 1908.

Application filed May 29, 1907. Serial No. 376,300.

To all whom it may concern:

Be it known that I, COLEMAN A. TERRY, a citizen of the United States of America, and a resident of the borough of Manhattan, of the 5 city of New York, county and State of New York, have invented certain new and useful Improvements in Core-Drilling Apparatus, of which the following is a specification, reference being had to the accompanying drawings, forming a part thereof:

My invention relates to improvements in core drilling apparatus, and particularly to feeding means employed therein. In this class of apparatus it has been common in the 15 past to employ what is known as a rope feed, such feed comprising winding drums arranged upon opposite sides of the central drill rods, with ropes connected to the said drill rods through some intermediate means, 20 such for instance as by connecting them with arms extending from the water swivel, which is located at the upper end of the said drill rods. There have been some serious objections, however, to this form of feeding mechanism, in that such feed has a tendency to cause the drill to drift, that is to say, to drill 25 its hole out of plumb. This has been caused first by the fact that the ropes sometimes wind up and unwind unevenly on the two 30 drums, so that the pull upon the drill rod is not in a straight line, and, second, should the rope on one drum overlap previous coils, a greater length of rope would be wound up in 35 a single revolution of that drum, than would be wound up on the drum on the other side if the rope thereon did not so overlap. This would cause a greater pull on the rope on one side of the drill rods than upon the other.

There is always more or less tendency for a 40 core drill to drift, and the greatest pains has to be taken to prevent this occurrence. Anything, therefore, which would be liable to increase this tendency to drift must be avoided, and hence a rope feed, though otherwise the 45 ideal feed for this class of drill owing to its flexibility, has been brought into disrepute. In my present invention I have devised means whereby the pull on the drill rods shall be equalized, so that the tendency to cause 50 same to drift will be entirely overcome. I employ a yoke which surrounds the upper drill rod and water swivel thereon, said yoke being connected by means of freely swinging links to a collar or bushing, which is in turn 55 mounted between upper and lower anti-friction bearings upon the journal of the said

water swivel; and I have then connected the ends of the ropes from the feed drums to the ends of arms extending from the said yoke. Under this construction, if one rope should be fed to a greater degree than the other, the 60 said yoke may swing upon its pivot, while if lateral pressure is applied thereto, the said yoke may swing laterally through the said links.

In order that my invention may be fully understood, I will now proceed to describe an embodiment thereof, having reference to the accompanying drawings, illustrating the same, and will then point out the novel features in claims.

In the drawings: Figure 1 is a front view of such part of a core drilling apparatus as is necessary to illustrate my invention, showing a feeding mechanism embodying my invention employed in connection therewith. Fig. 2 is a view in central longitudinal section through the water swivel and yoke employed therewith. Fig. 3 is a top view of the yoke with a portion of the water swivel shown in 70 horizontal section.

The drill itself, which is shown somewhat conventionally, includes hollow drill rods 5 and a rotating means 6. A water swivel 7 is secured to the drill rods at the upper end 75 thereof, said water swivel comprising a journal 8, a connecting sleeve 9 by which the said journal is connected to the drill rods, a bushing 10 loosely surrounding the journal 8, an anti-friction bearing 11 between the said 80 bushing and a shouldered portion of the said journal, another anti-friction bearing 12 arranged above the said bushing 10, a nut 13 confining the said bearings and bushing upon 85 the journal, and a spindle 14 arranged within the journal 8, and also confined in position by the said nut 13. The spindle 14 is screw-threaded at its upper end, to which is fitted an elbow 15 by which water is admitted to 90 the core drill for purposes well known. When the drill rods are rotated the journal 8 is rotated therewith together with the nut 13 and portions of the bearings 11, 12. The other 95 portions of the bearings 11, 12 remain stationary, as do also the bushing 10 and the spindle 14. A bail 16 is secured to the said bushing 10 by which the drill rods may be lifted when desired, said bail being connected to said bushing by means of screws 17. At 100 right angles to the screws 17 the said bushing 110 has links 18 connected thereto, one upon each side thereof, said links being pivotally con-

nected by means of screws 19. At their lower ends the said links 18 are pivotally connected by means of screws 20 to a yoke 21, said yoke surrounding the lower end of the 5 journal 8 of the water swivel. The yoke is provided with laterally extending arms 22 formed at the end thereof with recesses adapted to receive and form an anchorage for rope ends. The yoke is so constructed 10 as to be permitted free lateral play to a limited extent with respect to the water swivel, the opening 23 therethrough being sufficiently elongated in a lateral direction to permit such play, as will be clear by reference 15 to Figs. 2 and 3 of the drawings.

Feed ropes 24 are connected at their upper ends to the arm 22 of the yoke 21, and at their lower ends are taken up upon feed drums 25. Said feed drums are mounted 20 upon a shaft 26 journaled in suitable bearings 27, rotative feeding movements being imparted to the shaft 26 and drums 25 by any desired means. Should now the ropes coil or uncoil unevenly upon the drums 25, 25 the yoke 21 will, by means of the link connection 18, be permitted to swing laterally, so that no lateral pressure will be imparted to the drill rods as they are being fed forward. Similarly, if one rope 24 should be wound up 30 a little faster than the other, the swinging movement which the yoke 21 is free to make will compensate therefor, and even longitudinal pressure will be exerted upon the drill rods. The anti-friction bearing between the 35 bushing 10 and the shouldered portion of the journal 8 will also tend to increase the efficiency of the machine and to decrease friction and wear of the parts.

What I claim is:

- 40 1. In core drilling apparatus, the combination with a drill rod and rope feed therefor comprising winding means and ropes arranged to be wound thereon, of an equalizing yoke to which the upper ends of said ropes 45 are attached, said equalizing yoke having a pivotal connection with said drill rod.
2. In core drilling apparatus, the combination with a drill rod and rope feed there-

for comprising winding means and ropes arranged to be wound thereon, of an equalizing 50 yoke to which the upper ends of said ropes are attached, a collar for transmitting feeding movements to said drill rod, and links connecting said collar with said yoke.

3. In core drilling apparatus, the combination with a drill rod and a water swivel having a journal secured to the upper end of said drill rod, of a bushing mounted on said journal, an anti-friction bearing beneath said bushing and forming a thrust bearing 60 between said bushing and the said journal in a longitudinal direction, an equalizing yoke concentric with said collar and located beneath same, links pivotally connected to said yoke and said collar, whereby said yoke is suspended from said collar, said yoke permitted free lateral movement, winding means for imparting longitudinal movements to the yoke, and parts connected thereto, and ropes upon said winding means 70 connected at their outer ends to said yoke.

4. In core drilling apparatus, the combination with a drill rod and a water swivel at the upper end thereof comprising a journal 8, a connecting sleeve 9 for connecting the 75 said journal with said drill rod, and a nut 13 upon said journal, of a bushing 10 mounted upon said journal, anti-friction bearings 11 and 12 mounted above and below the said bushing, links 18 pivoted at their upper ends 80 to said bushing, a yoke 21 pivoted to the said links at their lower end, said yoke surrounding the said journal but permitted lateral movement with respect thereto, and having arms 22 extending in the line of said 85 lateral movement, winding drums 25 having their peripheries in line with the said yoke arms 22, and ropes 24 upon said winding drums having their upper ends connected to the arms 22 of said yoke 21, substantially 90 as set forth.

COLEMAN A. TERRY.
